CLOSURE CAP

Kyle E. Stant, Connersville, Ind.

Application October 1, 1932. Serial No. 635,840

7 Claims. (Cl. 220—24)

It is the general object of this invention to provide a closure cap having means permitting quick attachment and detachment to container filler spouts or tank openings.

5 An important object of the invention is to provide in a hinge type closure cap comprising a collar and lid, clamping means permitting the collar to be quickly secured to the filler spout against both rotation and axial displacement relative to the spout.

Another object of the invention contemplates construction permitting an unobstructed opening through the center of the collar having substantially equal area with the filler tube opening, for 15 entrance of a round nozzle.

It is a further object of the invention to provide universal clamping hooks on the collar which function to secure a specific collar tightly to any 20 number of different filler spouts having flanges thereon of variable heights and widths.

This, as well as other objects, will become more apparent upon consideration of the drawing and description specifically related thereto.

Fig. 1 is a plan view of a collar carrying the 25 clamps constituting details of my invention.

Fig. 2 is a sectional elevation of the complete 30 filler top embodying my invention, mounted upon a filler spout, also shown in section.

Fig. 3 is an inverted plan view of the filler top 35 embodying my invention, mounted in position on a spout, the section of which is taken on the line 3—3 of Fig. 2.

Fig. 4 is a fragmental perspective view of the 40 collar which constitutes an important detail of my invention.

Fig. 5 is a perspective view of a clamp which 45 cooperates with the collar shown in Fig. 4, and which constitutes another detail of my invention.

Fig. 6 is a fragmental sectional elevation taken 50 on line 6—6 of Fig. 1, showing the cooperation between the collar, the clamp, and the filler spout at the time my improved filler top structure is being placed in position on the spout for the purpose of fastening it thereto.

Fig. 7 is a view similar to Fig. 6, but showing 55 the next step taken and the position assumed by the parts of the structure I have disclosed, following the initial step disclosed in Fig. 6.

Fig. 8 is a view similar to Figs. 6 and 7, but 60 showing the completely mounted and clamped relationship of the parts of the structure embodying my invention, in which the collar and clamp are shown in locked condition on the filler spout.

Fig. 9 is a fragmental sectional elevation showing a structural variation of the clamp and screw 65

in cooperation with the collar and spout. The screw and clamp in the structure function in a substantially horizontal plane.

The principal elements embodied in my invention are a collar 11 which is to be mounted upon 60 the filler spout 12, and clamps 13 which, at suitable intervals about the inner periphery of the collar, are adapted to engage and lock the collar to the filler spout 12, as shown and as will be described. Cooperating with these elements is a closure cap 14 which is mounted upon the collar in a manner to prevent the escape of fluid from the tank equipped with the filler spout 12, and which is attached to the collar by means of a hinge 15 so that the cap may be swung free from interference with the opening through the collar and yet be held against loss, or detachment therefrom. The construction of the cap, its seal, and the hinge by means of which it is attached to the collar, do not constitute any part of this invention and will not be described specifically herein. 75

In the conventional filler spouts of the type employed on the fuel tanks and radiators of automobiles, the upper edge of the filler spout is provided with an inwardly or outwardly extending 80 lugged flange which is designated generally by the reference numeral 16. I have utilized this flange as the locking medium by which the collar 11 of my invention is secured in locked condition upon the filler spout, as I have shown in

85 the drawing and as now will be described. The collar 11 is provided with a shoulder 17 which carries an annular gasket 18 by means of which a fluid-tight joint is formed between the collar and the filler spout. At intervals about the inner wall of the collar 11 I have provided lugs 19 and 20, between which a groove 21 is provided for the reception of the clamp 13, two of such 90 grooves, located at diametrically opposite positions, having been provided on the collar. In

order that these clamps may be secured in position in their mounting grooves, I have provided a screw threaded opening 22 in the bottom wall of each groove and extending through the collar, for the reception of a screw 23 having a tapered shoulder, passing through the opening 24 of each clamp and adapted to secure the clamp in 95 position, as now will be described.

Each clamp jaw is provided with a depending lower end or finger 25 extending along side of the 100 flange 16 and may have a projecting lug 26 which may engage the lower edge of the flange when the collar is secured in position on the filler spout in the following manner. The first operation in mounting the collar in position on the filler spout, 105

110

is to place the screw 23 of each clamp jaw 13 through its opening 24 and to engage it with the threaded opening 22 of the collar, so that the clamp jaw is loosely positioned on the screw, as shown in Fig. 6, whereby, when the collar is brought to this position with relation to the filler spout, the clamp jaw 13 and its lug 26 will occupy the relationship to the spout flange 16, which will permit the collar to be brought into engagement with the upper edge of the spout, as shown in Fig. 7, in which position the clamp jaws will be forced to engage the spout flange 16, with their lugs 26 extending beneath the lower edge of the spout flange. The next operation is to bring the head of screw 23 toward clamp 13 until the clamp jaw is held lightly, but against looseness and the tapered shoulder is adjacent the clamp hole 24, whereby the clamp jaw face will be pressed against the edge of the spout flange as shown in Fig. 7. In this position it will be observed that the upper end 27 of the clamp jaw occupies an angular placement with relation to the cooperating surfaces of the under head of the screw and the bottom of the groove 21. With the parts in this condition, the screw 23 is now tightened until the angular position of the clamp end 27 has been changed to bring it into alignment with the cooperating surfaces of the screw head and clamp groove 21 and the tapered shoulder of screw 23 is in the hole 24, as shown in Fig. 8. The result of this final operation of securing the clamp in locked condition is, that the depending clamp jaw end 25 has been made rigid or brought to a "set", in which substantial unity of the collar, the spout, and the clamp jaw, relatively to each other, has been obtained.

It will be observed that the inaccessible lug 26 of each clamp jaw, apparently performs no function. However, the value of this lug consists in its ability to lock the filler top structure against forced removal, other than that permitted by proper lifting of the cap 14 in order that the heads of the screws 23 may be rendered accessible. These features of concealed locking means, are particularly valuable in such structures as will be found in filler top or cap constructions provided with key or permutation locks of the combination type which are provided for preventing unauthorized or unlawful access to the contents of the tank, for the purposes of theft, malicious destruction of property, and the like. Also, it will be observed that the depending portions 25 of the clamp jaws, may function rigidly or may yield or bend, relative to the ends 27 either through a spring-like tendency or through the acquisition of a "set", as may be preferred, in fastening the collar 11 in position on the filler spout as has been described.

The variation of the clamp structure as shown in Fig. 9 is thus described. A sleeve 28 is formed integral with the end 27 of the clamp jaw 13, the depending portion 25 of the clamp jaw is formed at an obtuse angle with the end 27, the screw 23 is fitted closely to the inside diameter of the sleeve 28, the walls 19 and 20 on the collar prevent the clamp from rotating when the screw is turned, thus causing the clamp to travel in a horizontal direction. As the screw is tightened the end 25 of the clamp jaw is forced outwardly beneath the spout flange and because of the angular shaped end 25 the collar is drawn down tightly upon the spout.

A point to which I draw attention is that my improved clamp structure for closure caps has been so designed as to leave the greatest pos-

sible maximum area through the center portion of the collar for the insertion of the conventional liquid filling nozzle.

Another detail to which I draw attention is that the clamp jaws are so shaped that their form enables them to engage the edge of the flange 16 of the filler spout or neck, so that when the clamp jaws are forced outwardly by their mounting screws, this formed clamp will operate to draw the collar closer to the filler spout, to thereby compress the gasket beneath the collar and effect a liquid seal between the collar and spout.

In view of the foregoing, it is obvious that the clamp jaw may be a rigid element which, by slidably engaging the locking flange of the filler spout, will be forced to clamping condition by the cooperating screw which mounts the clamp jaw, thereby creating a cam-like action of the clamp jaw on the locking flange of the filler spout.

While I have shown the preferred form of my invention as known to me it will be understood that various changes in the combination, construction, and arrangement of the parts may be made by those skilled in the art without departing from the spirit of the invention as claimed.

Having thus described my invention, what I claim and desire to secure by Letters Patent is:

1. A closure for receptacles comprising, in combination, a filler spout having a flange, a collar adjacent the flange, a cover pivoted to said collar, means for detachably locking said cover to the collar, clamp jaws adapted to move in a substantially horizontal direction, separate movable means carried by the collar for moving said clamp jaws in slidable engagement with the flange, said means adapted to simultaneously draw the clamp into tight engagement with the collar and spout flange and the collar into tight engagement with the spout.

2. A closure for receptacles comprising, in combination, a filler spout having a flange, a collar adjacent said flange, a lockable cover pivoted to said collar, clamping means carried by said collar comprising, a clamp member and a separate screw means associated with the clamp member and collar, said screw means adapted to force said clamp member into slidable engagement with said flange, whereby the collar and clamp may be drawn into tight engagement with the filler spout.

3. A closure cap for a flanged filler tube or the like, comprising, in combination, a collar arranged to cooperate with the flanged end of the filler tube, a lockable cover for the collar, clamping means on said collar consisting of a separate clamp member and means for forcing one end of said clamp member against the collar and the other end substantially horizontally into slidable engagement with the filler tube flange, whereby the collar is clamped on said tube.

4. A closure cap for a receptacle, comprising, in combination, a flange on the receptacle, a collar adapted to cooperate with said flange, a lockable cover hinged to said collar, clamp means on said collar having flange engaging means thereon, horizontally extending screw means associated with the collar and clamp means, whereby the flange engaging means is forced substantially horizontally under said flange while the other portion of the clamp means is retained by said screw means in substantially pivotal relation to said collar, whereby the collar is clamped to said flange.

5. A closure for receptacles comprising, in combination, a filler tube, a collar mounted on the tube, interlocking elements associated with the collar and tube, comprising, a projecting flange, and a separate angular clamp member movable in a substantially horizontal direction and adapted to slidably engage the flange, one of said interlocking elements being on the spout and the other on the collar, whereby the collar and spout may be clamped together.

10. In combination, in a closure, a spout having a flange thereon, a collar mounted on the spout, a clamp member on said collar having an angular depending portion, means on the collar adapted

to force the said depending portion in a substantially horizontal direction relative to the collar and flange, whereby the collar may be clamped to the spout.

7. In combination, in a closure, a spout having a flange thereon, a collar mounted on the spout, a clamp member on said collar having a depending finger with a lug thereon, screw means on the collar adapted to force the finger in a substantially horizontal direction, whereby the collar may be clamped to the spout with the lug on said finger disposed below said flange.
